MACHINES FOR SHAPING UPPERS OVER LASTS

Charles K. Woodman, Beverly, Mass., assignor to United Shoe Machinery Corporation, Flemington, N.J., a corporation of New Jersey

Application December 23, 1955, Serial No. 554,994

8 Claims. (Cl. 12—10.2)

This invention relates to machines for shaping uppers over lasts, and is herein illustrated as embodied in a pulling over machine of a well-known type. It will be understood, however, that in their broader aspects features of the invention are not limited to use in a pulling over machine of this particular type or to the exact mechanical arrangement herein shown.

During the pulling over operation as performed, for example, on a pulling over machine of the type herein illustrated, the upper materials are positioned in a lengthwise direction, relatively to the toe end of the last, by a manual manipulation of the toe gripper effected by the operator, during a dwell in the operating cycle of the machine, which manipulation may consist of a further movement of the gripper to pull the upper materials to the desired location or, if the initial pull of the toe gripper has already pulled the upper materials too far toward the toe end of the last, the operator may, while holding the gripper against movement by its operating spring, open the gripper to permit the upper materials to retract to the desired location. In either case, this operation involves the exercise of considerable effort and care on the part of the operator and takes a substantial amount of time. It is, therefore, a principal object of the present invention to provide, in a pulling over machine, means for so facilitating this operation that the upper materials may be brought to the desired location relatively to the toe end of the last with greater accuracy and speed and also with little or no effort on the part of the operator.

With this object in view, the herein illustrated machine which, in common with pulling over machines of the type hereunder consideration, has a toe gripper which is actuated by power operated means including a yieldable connection for imparting movement to the toe gripper in a direction extending heightwise of a last, is provided with mechanism for arresting the movement of the toe gripper during the operation of the power operated means just before the upper materials have been pulled to the desired location on the last and operator controlled means for selectively releasing and reengaging the gripper arresting mechanism to cause a controlled additional movement of the gripper by the yieldable means. More particularly, the power operated means includes a cam and a spring for imparting movement to the gripper, while the mechanism for arresting movement of the gripper comprises a fluid brake and a valve which is arranged to be automatically closed to bring the brake into action when the toe gripper has been moved to pull the upper materials to an adjustably predetermined position on the last. Manual means are also provided for opening another valve to release the brake so that the operator, by repeatedly opening and then closing the last-named valve, can cause the gripper arresting mechanism to release and reengage the gripper and thereby effect a very accurately controlled additional movement of the gripper by the spring until the upper materials have been brought to the desired location on

2

the last. Preferably, and in the herein illustrated machine, the mechanism for arresting the movement of the toe gripper is arranged to be automatically adjusted, in response to adjusting movements of the toe gripper lengthwise of the shoe, to vary the extent of movement of the gripper so as to accommodate shoes of different sizes and, further to facilitate the operation of pulling the upper materials to the proper lengthwise location on the last, the herein illustrated machine is provided with a visual indicating means.

The above and other objects and features of the invention will be apparent in the following detailed description of the preferred embodiment which is illustrated in the accompanying drawings, and will be pointed out in the claims.

In the drawings,

Fig. 1 is a view in side elevation of a pulling over machine embodying features of the present invention, shown with certain parts of the machine broken away and others omitted to simplify the disclosure;

Fig. 2 is a view in front elevation of a portion of the machine shown in Fig. 1;

Fig. 3 is a view in perspective of another portion of the machine;

Fig. 4 is a view in side elevation of that portion of the machine shown in Fig. 3 with certain parts in vertical section;

Fig. 5 is a view in section substantially on line V—V of Fig. 4 and looking in the direction of the arrows;

Fig. 6 is a view in perspective of another portion of the machine with certain parts shown in section;

Fig. 7 is a plan view of a portion of a shoe in the machine; and

Fig. 8 is a schematic drawing illustrating control mechanism associated with the machine.

Referring to the drawings, and particularly to Fig. 1 thereof, the invention is therein illustrated as embodied in a pulling over machine of the type disclosed in United States Letters Patent No. 1,029,387, granted on June 11, 1912, on an application filed in the name of Ronald F. McFeely, modified in some respects in accordance with the disclosure of United States Letters Patent No. 2,007,973, granted on July 16, 1935 on an application filed in the name of Bernhardt Jorgensen. Thus, this machine has a toe gripper 10 and a pair of side grippers 12, one of which is shown, for seizing the upper materials at the extreme end and at the opposite sides of the toe of a shoe and for moving heightwise of a last to exert a pull to stretch the upper materials U over the last, together with overlaying and fastener inserting devices, one of which is shown and indicated by the reference character 14, for wiping the lasting margin of the tensioned upper materials inwardly over and for securing it to the bottom of a shoe at the end and opposite sides of the toe of the shoe. During the operation of the machine, the shoe on its last is supported on a shoe rest 16 and, prior to the operation of the overlaying and fastener inserting devices, the upper is clamped to the opposite sides of the toe end of the last by a pair of clamp members, one of which is indicated generally by the reference character 18. The mentioned operating elements are mounted on and operated by mechanism contained within a main frame 20 and include a main cam shaft which is driven through a suitable clutch under the control of a foot treadle, not shown.

The toe gripper 10 is connected to an operating lever 30, having a hand grip portion 32 and a gripper control member 34 associated therewith, and this lever is adapted to be actuated by power operated means including a cam, not shown, and an operating slide 36 which is connected to one arm of the lever 30, through a yieldable

connection provided by a spring 38. In a like manner, the two side grippers 12 are connected to operating levers 40, one of which appears in Fig. 1, and these levers are adapted to be actuated by another cam, not shown, an operating slide 42, and another spring 44. As is usual in machines of this type, the herein illustrated machine has a manually operable lever arm 50 and mechanism whereby the movements of the side grippers may be controlled during the operation of the machine, see Patent No. 2,007,973, referred to above.

It will be understood that pulling over machines of the type herein illustrated operate in a cycle having two distinct stages, during the first of which the toe and side grippers are closed on the upper materials and then are actuated to exert a pull to stretch the upper materials over the last, whereupon the machine comes to a stop with the upper materials under tension. The operator now has an opportunity to inspect the upper and to determine if it is properly located on the last and suitably stretched thereover. After making appropriate adjustments in the location of the upper by manipulation of the toe and/or side grippers, the machine is again started by a second depression of the treadle, and during this second stage in the operating cycle, the overlaying fastener inserting devices are operated to wipe the lasting margin of the upper materials inwardly over and to secure said margin to the bottom of the shoe. One of the most frequent adjustments of the location of the upper materials relatively to the last which the operator is required to make is to shift the upper lengthwise of the last, by suitable manipulation of the toe gripper, effected by means of the hand grip portion 32 of the lever 30, in order properly to locate the tip seam T of the upper relatively to the toe end of the last. The herein illustrated machine is provided with mechanism about to be described which greatly facilitates this operation.

Referring to Fig. 1 of the drawings, the operating lever 30 is connected to one end of the rod 60 of a piston 62 (diagrammatically illustrated in Fig. 8) received within a cylinder 64 which is mounted on a portion of the machine frame 20. Also connected to the operating lever 30 is a control rod 66 which is cut away at 68 to provide a control cam portion 70. One end of this rod is slideable within a guide bore 72 in an upstanding ear 74 formed on a block 76, Figs. 3, 4 and 5. This block has a tongue 78 slideable in a guideway 80 formed in a member 82 which is mounted on an outwardly projecting portion of the machine frame 20, Fig. 5. Mounted on the block 76 is a normally closed microswitch M-1 having an operating plunger 84 which is in engagement with the cut-away portion 68 of the control rod 66 when the machine is idle, see Fig. 8. Connected to the opposite ends, respectively, of the cylinder 64 are two conduits 90, 92 which are joined by two cross-connecting conduits 94, 96.

Located in the cross-connecting conduit 94 is a solenoid operated valve S-1 having a coil 98, while located in the cross-connecting conduit 96 is a similar solenoid operated valve S-2 having a coil 100. These valves are of conventional construction and each includes a valve plunger, not shown, which is adapted to be held in closed position by a spring, not shown, and to be moved to open position by an armature when its coil is energized. The cylinder 64 and conduits 90, 92, 94 and 96 are entirely filled with fluid, such as oil, by means of a filler funnel 102, pipe 104, and a shut-off valve 106, Figs. 1 and 2. Referring to Fig. 8, the coil 98 of valve S-1 is directly connected to one end of a lead 110 and at its other end is connected to another lead 112 through the microswitch M-1 and/or a second microswitch M-2. The coil 100 of the valve S-2 is likewise connected at one end to the lead 110 and at its other end is connected to the lead 112 through a microswitch M-3. The leads 110 and 112 are connected to a suitable source of electrical energy, not shown. Also interposed in the cross-connecting

conduit 96 is a needle valve 114 which is diagrammatically illustrated in Fig. 8.

When the machine is at rest, the control rod 66 occupies the position shown in Fig. 8 with the plunger 84 of the switch M-1 engaging the cut-away portion 68 of the rod so that the switch M-1 is closed to energize the coil 98 of the valve S-1. Accordingly, when the toe gripper is actuated during the initial stage of the operating cycle of the machine, the piston 62 moves freely within the cylinder 64 as fluid flows freely between the opposite ends of the cylinder through conduits 90, 92 and 94 and the open valve S-1, valve S-2 at this time being held closed by its spring, since coil 100 thereof is deenergized. Eventually the control cam portion 70 of the rod 66 engages the plunger 84 and opens the switch M-1, thereby deenergizing the coil 98 and causing the valve S-1 to be closed by its spring. Continued movement of the piston 62 and hence of the toe gripper is now arrested by the fluid trapped in the upper portion of the cylinder 64, and in conduits 90 and 94. Therefore, as the toe gripper cam completes its operating movement, the spring 38 will be further compressed to absorb the throw of this cam.

The block 82 is so positioned and the cam portion 70 of the control rod 66 is so located that movement of the toe gripper is thus arrested just before the upper materials have been drawn forwardly by the toe gripper to the desired location lengthwise of the last. Now, after the machine has come to a stop at the conclusion of the initial stage of its operating cycle with the toe and side grippers exerting their pulls on the upper materials, the operator can release the toe gripper for further movement under the action of the compressed spring 38 by closing the switch M-3 and thereby energizing the coil 100 of the valve S-2 and causing this valve to open. Fluid now can flow through the cross-connecting conduit 96 at a measured rate, as determined by the setting of the needle valve 114. Thus, by repeatedly opening and closing the switch M-3, which has an operating plunger 116 and is conveniently located on the lever arm 50, Fig. 1, the operator can "inch" the toe gripper along and very accurately locate the upper materials lengthwise of the last.

During the second stage of the operating cycle of the machine, and just before the toe and side grippers are opened to release the upper materials, the side clamps 18 are moved inwardly to clamp the upper against the last. The switch M-2, referred to above, is adapted to be closed by one of the arms which carries a side clamp when the clamp is thus moved inwardly, thereby energizing the coil 98 and opening the valve S-1 to free the toe gripper 10 for movement away from the shoe after this gripper has been opened to release the upper materials. If desired, a fourth microswitch M-4 may be interposed in the lead 112, see Fig. 8, and arranged to be opened when the machine is at rest, i.e., before or after each complete operating cycle, thereby to prevent overheating of the coil 98 of the valve S-1. As is illustrated in Fig. 2, the valves S-1 and S-2 are supported on an arm 120 which is secured to one of two brackets 122, 122 by means of which the cylinder 64 is mounted on the frame 20 of the machine.

As is shown in Fig. 1, the control rod 66 is made in two parts, the uppermost of which is enlarged at 130, provided with a bore to receive the lower part which is secured therein by means of a setscrew 132. By loosening this screw, the lower part of the control rod may be shifted relatively to the upper part, thereby to change the position of the cam portion 70 with respect to the operating plunger 84 of the switch M-1. Thus, the amount of movement of the toe gripper 10, prior to the closing of the valve 98, may be accurately adjusted. In addition to this adjustment, the herein illustrated machine is provided with means for automatically changing the position of the switch M-1 and of its operating plunger 84, relatively to the control rod 66 and its cam portion 70.

to accommodate shoes of different sizes. In common with pulling over machines of the type disclosed in the above-mentioned patents, the herein illustrated machine is provided with mechanism for simultaneously shifting the toe and side grippers toward or away from the shoe rest 16, this mechanism including a hand knob 140, Fig. 1, and a positioning member 142 against which the toe gripper is held by means of a spring, not shown.

Referring to Figs. 3, 4 and 5, secured to one side of the block 76 on which the switch M-1 is mounted, is a rack 160 and meshing with this is a pinion 162. This pinion is pressed onto the hub of a second pinion 164 which is journaled on a stud 166 mounted on a side plate 168, associated with the member 82. Meshing with the pinion 164 is a second rack 170 which is slidably mounted in a guideway 172 formed in a block 174, secured to the frame member 20 by means of a screw 176. An enlarged end 180 formed on this rack, is held yieldingly in engagement with a pressure surface 182 formed on the toe gripper 10 by means of a coil spring 184 which bears against a pin 186 carried by the rack. As will be apparent, when the toe gripper 10 is moved toward the shoe rest 16, to accommodate a smaller shoe, the rack 170 will move downwardly, as viewed in Fig. 4, and, through the action of the pinions 162, 164, will cause the block 76 and the switch M-1 carried thereby, to move downwardly, i.e., to the right as viewed in Fig. 4, thereby locating the plunger 84 of the switch M-1 closer to the cam portion 70 on the control rod 66. Thus the movement of the toe gripper to pull the upper material will be limited to a shorter distance before the gripper is brought to a stop as a result of the opening of the switch M-1 by the cam portion 70 on the control rod 66. Conversely, if the toe gripper 10 is moved away from the shoe rest, to accommodate a larger shoe, the switch M-1 will be moved upwardly, as viewed in Fig. 1, i.e., to the left as viewed in Fig. 4, thereby providing for a longer movement of the toe gripper before it is brought to a stop. The relative sizes of the two pinions 162, 164 are such that the mentioned decrease and increase in the amount of travel of the toe gripper is substantially proportional to the extent of gripper movement required for small and large shoes respectively.

As suggested above, the lower portion of the control rod 66 is so adjusted, relatively to its upper portion, and the switch M-1 is so located, relatively to the cam portion 70 of the control rod, that the pulling movement of the toe gripper 10 is arrested just before the upper materials U have been brought to the desired location lengthwise of the toe end of the last. Thereafter, the toe gripper is "inched" along as the operator closes and opens switch M-3 until the upper materials are brought to the desired location, i.e., until the tip line T is in the proper lengthwise position on the last. To assist the operator in determining when this proper position has been reached, the herein illustrated machine is provided with a visual indicator means.

The aforementioned indicator means comprises a triangular member 190 which is fastened to one of the offset ends of a rod 192, the other end of which is mounted in a block 194. This block is rotatably supported by means of a stud 196 in a member 198 which is supported on a portion of the machine frame 20 by means of a bracket 200, see Fig. 6. A coil spring 202 tends to hold the block 194 yieldingly against an end face 204 of the member 198 with the end of a pin 206 extending into a hole (not shown) in the member 198. With this arrangement, the block 194 may be pulled slightly away from the member 198 and then rotated to swing the member 190 to an inoperative position. The member 190 is made of transparent material such as glass or plastic and has on it two lines R and L. These lines indicate, respectively, the proper lengthwise position (and also the proper angular position) of the tip

line of the upper of right and left shoes. Therefore, after the pulling movement of the toe gripper has been arrested in the manner explained above, the operator, after manipulating the side grippers in the usual manner to bring the tip line into parallelism with the proper line R or L, may then "inch" the toe gripper along until the tip line T coincides with that line.

Having thus described my invention, what I claim as new and desire to secure by Letters Patent of the United States is:

1. In a machine for shaping uppers over lasts, a gripper for seizing the upper of a shoe and movable thereafter in a direction extending heightwise of a last to tension the upper over the last, power operated means including a yieldable connection for imparting movement to the gripper, means including a brake device for arresting the movement of the gripper during the operation of said power operated means in response to movement of the gripper to an adjustably predetermined position, and means under the control of the operator for selectively releasing and reengaging the brake device to effect a controlled additional movement of the gripper to any selected position within its range of movement by said yieldable connection.
2. In a machine for shaping uppers over lasts, a gripper for seizing the upper of a shoe and movable thereafter in a direction extending heightwise of a last to tension the upper over the last, power operated means including a spring for imparting movement to the gripper, means including a brake device connected to the gripper for arresting the movement of the gripper during the operation of said power operated means in response to movement of the gripper to an adjustably predetermined position, and means under the control of the operator for selectively releasing and reengaging the brake device to effect a controlled additional movement of the gripper to any selected position within its range of movement by said spring.
3. In a machine for shaping uppers over lasts, a gripper for seizing the upper of a shoe and movable thereafter in a direction extending heightwise of a last to tension the upper over the last, power operated means including a spring for imparting movement to the gripper, means including a fluid brake device connected to the gripper for arresting the movement of the gripper during the operation of said power operated means in response to movement of the gripper to an adjustably predetermined position, and means under the control of the operator for selectively releasing and reengaging the brake device to effect a controlled additional movement of the gripper by said spring.
4. In a machine for shaping uppers over lasts, a gripper for seizing the upper of a shoe and movable thereafter in a direction extending heightwise of a last to tension the upper over the last, said gripper being adjustable in a direction extending lengthwise of a shoe in the machine to accommodate shoes of different sizes, power operated means including a yieldable connection for imparting movement to the gripper, means connected to the gripper and operable to arrest the movement of the gripper during the operation of the power operated means when the gripper has moved to a predetermined position, said means including a member movable in response to adjustment of said gripper to vary said predetermined position, and means under the control of the operator for selectively releasing and reengaging the gripper arresting means to effect a controlled additional movement of the gripper by said yieldable connection.
5. In a machine for shaping uppers over lasts, a gripper for seizing the upper of a shoe and movable thereafter in a direction extending heightwise of a last to tension the upper over the last, said gripper being adjustable in a direction extending lengthwise of a shoe in the machine to accommodate shoes of different sizes, power operated means including a spring for imparting movement to

7
the gripper, means connected to the gripper and operable to arrest the movement of the gripper during the operation of said power operated means when the gripper has moved to a predetermined position, said means including a member movable in response to adjustment of said gripper and adapted to vary said predetermined position, and means under the control of the operator for selectively releasing and reengaging the gripper arresting means to effect a controlled additional movement of the gripper by said spring.

6. In a machine for shaping uppers over lasts, a gripper for seizing the upper of a shoe and movable thereafter in a direction extending heightwise of a last to tension the upper over the last, said gripper being adjustable in a direction extending lengthwise of a shoe in the machine to accommodate shoes of different sizes, power operated means including a yieldable connection for imparting movement to the gripper, means including a brake device for arresting the movement of the gripper during the operation of said power operated means when the gripper has moved to a predetermined position, said means including a member movable in response to adjustment of said gripper and adapted to vary said predetermined position, and means under the control of the operator for selectively releasing and reengaging the brake device to effect a controlled additional movement of the gripper by said yieldable connection.

7. In a machine for shaping uppers over lasts, a gripper for seizing the upper of a shoe and movable thereafter in a direction extending heightwise of a last to tension the upper over the last, said gripper being adjustable in a direction extending lengthwise of a shoe in the machine to accommodate shoes of different sizes, power operated means including a spring for imparting movement to the gripper, means including a brake device connected to the

8
gripper for arresting the movement of the gripper during the operation of said power operated means when the gripper has moved to a predetermined position, said means including a member movable in response to adjustment of said gripper and adapted to vary said predetermined position, and means under the control of the operator for selectively releasing and reengaging the brake device to effect a controlled additional movement of the gripper by said spring.

10 8. In a machine for shaping uppers over lasts, a gripper for seizing the upper of a shoe and movable thereafter in a direction extending heightwise of a last to tension the upper over the last, said gripper being adjustable in a direction extending lengthwise of a shoe in the machine to accommodate shoes of different sizes, power operated means including a spring for imparting movement to the gripper, means including a fluid brake device connected to the gripper for arresting the movement of the gripper during the operation of said power operated means when the gripper has moved to a predetermined position, said means including a member movable in response to adjustment of said gripper and adapted to vary said predetermined position, and means under the control of the operator for selectively releasing and reengaging the brake device to effect a controlled additional movement of the gripper by said spring.
